UNITED STATES PATENT OFFICE.

ARTHUR PAULSON, OF NEW YORK, N. Y., ASSIGNOR TO CHRISTIAN IVERSON, INC., OF NEW YORK, N. Y.

PASTE JAR.

Application filed October 20, 1925. Serial No. 63,674.

My invention relates to a new and improved jar or container for liquids or pastes such as mucilage, glue, library paste, etc. of the type shown in my co-pending application for paste 5 jar, Serial Number 35,405 filed June 6, 1925.

It is usual at present to provide these jars with a brush for applying the contents, either carried in a compartment in the jar or mounted in a rigid tin cap. When the brush is used, 10 it is very often wiped against the neck of the jars either to remove excess material or because of awkwardness in replacing the brush. Furthermore as the supply in the jar becomes low, it is more and more difficult to reach it 15 with the brush. As a result both jar and brush soon become messy and sticky and inconvenient to handle.

It is an object of my invention to provide a brush holder, and cooperating means inside 20 the jar, so arranged as to reduce the possibility of the aforementioned occurrences even in careless use of the brush.

A further object of my invention is to provide a mounting for the brush which shall 25 also act as a closure for the jar and be so arranged as to easily and accurately slip into position.

A further object of my invention is to provide a mounting for the brush which will permit of the brush being manipulated so as to 30 reach all parts of the container while maintaining effective closure.

Other and further objects will be apparent as the description proceeds.

To achieve these objects, I provide within 35 the jar a member having a wiping edge and mount the brush in a weighted rubber stopper fitting within the member, the stopper and member being shaped as to provide, in effect, 40 a ball and socket joint when the former is in position.

In the drawings I have illustrated an embodiment of my invention which I shall now describe in detail; but it is to be understood 45 that various changes and modifications may be made within the scope of my claims without departing from the spirit of my invention.

In the drawings:

50 Fig. 1 is an exploded view, in elevation of a jar constructed according to my invention.

Fig. 2 is a cross-sectional view in elevation showing all the parts assembled.

Fig. 3 is a view similar to that of Fig. 2, the brush mounting being shown in elevation and in a different position. 55

My container consists of a jar 1 adapted to contain a quantity of liquid or paste 2 and provided with a neck 3, a member 4, provided with a wiping edge inside the jar, and supported from the neck 3, a stopper and brush support 6, a brush 8 and a cover 9. 60

The wiping edge member consists of a hollow body 4 of spherical shape provided with a depending edge portion, a horizontal connecting portion 11 fitting upon the neck, and a depending part 5 screw-threaded to co-operate with screw-threads 3^a upon neck 3, provided with external screw-threads 13 to coact with screw-threads 16 upon cover 9, and 70 also provided with a depending tab 10 the purpose of which will presently appear. 65

The brush carrier consists of a semi-spherical mass of rubber or similar material adapted to fit into the hollow of member 4 and 75 moulded around or otherwise provided with the weight 7 of lead or other heavy material. Openings 14 and 15, to accommodate the stem of brush 8, are provided in 6 and 7 respectively. The opening 14 is shaped and proportioned to grip the brush stem with some force; but at the same time allow adjustment. 80

The cover 9 is provided with a flat upper surface 12 adapted to extend over the entire upper part of the jar and a depending skirt 85 adapted to thread on to member 5.

When the user first opens the jar, he places his thumb upon the tab 10 thus hold member 4 in position and unscrews the cover 9. This cover may then be thrown away as the brush 90 carrier 6 functions as a stopper. Of course the cover may be kept and used again especially if the paste is required only occasionally.

When the brush is lifted, any excess of material may be wiped off against the lower edge of 95 4 and drip back into the body of the material 2. On replacing the brush the stopper 6 will fit easily and naturally inside the member 4. Due to the presence of weight 7 the 100 brush end will naturally tend to enter the jar first and thus avoid touching the upper portions of member 4. The member 6 fits the hollow of 4 in almost any position and serves as an efficient closure. 105

In other words the hand of the user is

guided naturally and easily to replace the brush correctly and with the minimum of sloppiness.

When the supply of liquid in the jar runs low, the brush may be adjusted inwards through the opening 14. The elastic material of the brush carrier 6 permits this and at the same time provides a grip sufficiently firm to hold the brush in any adjusted position. The brush may be extended to any position necessary. Due to the shape of the engaging surfaces of 4 and 6, the brush 8 may be manipulated to reach every corner of the jar without decreasing the effectiveness of the closure.

Having thus described the nature of my invention, I claim:

1. A jar for liquids or pastes comprising a container, a member mounted in the container and shaped to provide a concave upper surface substantially entirely within the said container and a passageway communicating the interior and exterior of the jar, and means adapted to fit the said surface and act as a closure for the passageway.
2. A jar for liquids or pastes comprising a container, a member mounted to extend into the container and shaped to provide a concave, partly spherical upper surface substantially entirely within the said container and a passageway communicating the interior and exterior of the jar, and means adapted to fit the said surface and act as a closure for the passageway.
3. A jar for liquids or pastes comprising a container, a member mounted to extend into the container and shaped to provide a concave, partly spherical upper surface substantially entirely within the said container and a passageway communicating the interior and exterior of the jar, means adapted to fit the said surface and act as a closure for the said passageway, and a brush mounted in the said means in position to extend through the passageway.
4. A jar for liquids or pastes comprising a container, a member mounted to extend into the container and shaped to provide a concave, partly spherical upper surface substan-

tially entirely within the said container and a passageway communicating the interior and exterior of the jar, means adapted to fit said surface and act as a closure for the said passageway and a brush, adjustably mounted in the said means in position to extend through the passageway.

5. A jar for liquids or pastes comprising a container, a member mounted within the container and partly closing the same, removable means adapted to rest upon the said member substantially within the said container and act as a closure for the said container, the said member and means having engaging surfaces so shaped as to permit relative sliding motion without destroying the effectiveness of the closure.

6. A jar for liquids or pastes comprising a container, a member mounted within the container and partly closing the same, means adapted to rest upon the said member substantially within the said container and act as a closure for the said container, said member and said means having engaging surfaces shaped to permit relative sliding motion in a plurality of dimensions without destroying the effectiveness of the engagement and closure.

7. A jar for liquids and pastes comprising a container, a member mounted to extend within the container and provided with a wiping edge, securing means for the member adapted to attach to the outside of the container, a cover adapted to fit over the member and securing means, and means for holding the securing means in position when the cover is being removed.

8. A jar for liquids or pastes comprising a container, a member mounted to extend within the container and provided with a wiping edge, securing means for the member adapted to attach to the outside of the container, closure means for the jar fitting within the said member, and a cover adapted to fit over the said member, securing means, and closure means.

ARTHUR PAULSON.
